UNITED STATES PATENT OFFICE.

FRANK EDWARD LICHTENHAELER, OF NEWTON HIGHLANDS, MASSACHUSETTS.

APPARATUS FOR MIXING LIQUIDS.

Application filed December 13, 1923. Serial No. 690,480.

To all whom it may concern:

Be it known that I, FRANK E. LICHTENHAELER, a citizen of the United States, residing at Newton Highlands, in the county of Middlesex and State of Massachusetts, have invented certain new and useful Improvements in Apparatus for Mixing Liquids; and I do hereby declare the following to be a full, clear, and exact description of the invention, such as will enable others skilled in the art to which it appertains to make and use the same.

The present invention relates to an improvement in apparatus for mixing liquids.

The object of the invention is to produce a piece of apparatus by which liquids may be efficiently and intimately mixed together. For example, in the mixing of wort and yeast to be fermented, it is desirable that the mixture be intimate and uniform. So also in the mixing of various liquids for many purposes. To the above end the present invention consists in the mixer herein-after described and particularly defined in the claims.

In the accompanying drawings illustrating the preferred form of the invention, Fig. 1 is a perspective view of the mixer with a portion of the wall removed to show the general construction; and Fig. 2 is a sectional elevation.

The body of the mixer comprises a shell 1 which is provided with a bottom 2 and a top 3. The liquids to be mixed are introduced through the pipe 4 which enters the top at the center and descends vertically to a point close to a partition hereinafter referred to. In the illustrated embodiment the wort is introduced through the main pipe 5 and the yeast is introduced through the branch pipe 6. The principal body of liquid, of course, enters through the pipe 5, and the affluent through the pipe 6. These two liquids may be the same or different in amount, and in any case while they are admitted together through one pipe into the mixer they are not thereby intimately mixed, as one stream will flow alongside of the other for some time without intimately mixing therewith. The inlet pipe 4 discharges on a diffluent deck 7 provided at its center with a partition 8 which divides the deck 7 into two equal parts. The partition 8 is located in the center of the pipe 4 so that one-half the liquid entering through the inlet pipe is discharged on one side of the

partition, and the other half on the other side of the partition. The two portions of the liquid spread out upon the opposite sides of the partition and overflow the ends 60 of the deck 7 at 9 and 10, the decks terminating before they reach the walls of the shell. At 9 and at 10 the deck is turned downward to form lips 11 and 12 for the purpose of causing the liquid to be turned 65 downward by adhesion to the lip. These two discharges of the liquid fall upon a confluent deck 13, the adjacent edges of which are provided with downturned lips 14. The parts of the confluent deck 70 extend from the wall of the shell toward each other and leave an opening between their approaching edges through which the liquids may cascade against each other and fall upon the diffluent deck 15 below, which 75 is a duplicate of the diffluent deck 7 above, and by which the stream is again divided and allowed to fall in two streams upon the confluent deck 16.

The liquids falling upon the diffluent deck 80 7 are divided into two parts and each portion is more or less mixed up in striking with some force against the deck 7, and then further mixed by falling and splashing upon the two portions of the deck 13. Here 85 again further mixing and splashing together of the portions of the liquid is secured, and further splashing and mixing is obtained by discharging the liquids toward each other into the space between. This discharge is 90 divided again in the diffluent deck 15, and the two discharges from that deck are again recombined on the confluent deck 16. The repeated subdivisions of the stream and the repeated confluent 95 of the portions thereof cause a turbulence in the movements of the particles of liquid which results in an intimate mixture of the portions thereof.

The several decks are provided with upwardly turned flanges which are riveted and brazed to the walls of the shell. The partitions 8 are riveted and brazed to the diffluent decks and to the walls of the shell. In one aspect the stream is divided into two parts; those two parts are united into one stream which is again divided at right angles to its former path into two streams. It is therefore imaginable that the stream is halved and quartered and further divided into eighths and sixteenths, but the best, expert understanding of the operation of the apparatus is got by pointing out that the

stream is divided and portions are subjected to turbulent movement, the portions are again turbulently united and again divided and the uniting of the divided streams again secured. Throughout the entire mixer the process of mixing is carried on.

In the case of liquids which differ widely from each other in fluidity or viscosity, a greater number of decks would be required than in the case of easily miscible and more fluent liquids.

No power is required to operate the apparatus aside from the head of the liquids which flow in through the inlet pipe. The proper amount of relative quantities of liquid introduced should be regulated so that the desired quantity of each shall be admitted in the given time. Then the mixture flowing out from the bottom of the apparatus will be of uniform constitution at all times and homogeneously mixed.

It is within the purview of the invention to divide the stream into smaller fractions, to reunite such smaller fractions into one or a plurality of other streams again to be divided and reunited as before.

Having thus described the invention, what is claimed is:

1. An apparatus for mixing liquids having a vertical body provided with an inlet at the top for the liquids to be mixed, a diffluent deck upon which the liquids are discharged having a partition so located with respect to the inlet as to divide the incoming liquids into a plurality of parts, the deck having as many discharge places as the stream is divided into by the partition, a second confluent deck consisting of as many parts as there were streams upon it, each part located to receive a discharge from a part of the deck above and constructed and arranged to discharge all of the liquids received by the several parts into a common discharge opening.
2. An apparatus for mixing liquids having a vertical body provided with an inlet opening for liquids to be mixed together, a diffluent deck upon which the liquids to be mixed are received from the inlet opening, a vertical partition on the deck so located with respect to the inlet opening as to divide the entering stream of liquids into two parts, the deck being provided with an outlet for each such part, a confluent deck provided with two parts, one to receive the

discharge liquid from each discharge opening in the diffluent deck, and itself provided with a single discharge opening through which all of the liquids received on it are discharged.

3. An apparatus for mixing liquids having a vertical body, an inlet opening, a diffluent deck extending in one direction from wall to wall of the body and in a direction at right angles thereto toward but not to the wall of the body, a confluent deck below the diffluent deck having parts extending from the wall of the body toward a central opening for receiving the discharge from the diffluent deck and discharging it through the center opening.

4. An apparatus for mixing liquids having a vertical body provided with an inlet, a diffluent deck consisting of a plate attached at its ends to the wall of the body and having its sides extended toward the body leaving a space between such sides and the body to afford a discharge opening, said deck being provided with a partition extended longitudinally of the middle of the deck for dividing the deck into two parts, such partition being located to divide the stream of liquid entering the mixer into two parts, a confluent deck having two portions extending to the sides of the body under the openings in the diffluent deck above and toward each other, leaving an elongated opening between their contiguous ends, such opening being located in the plane of the partition of the deck above.

5. An apparatus for mixing liquids having a vertical body provided with an inlet in its end, a diffluent deck having a partition across it arranged to divide the area of the inlet so as to divert the inflowing liquid on to the two sides of the partition, outlets in the deck arranged parallel to the partition, a confluent deck below the inlet deck provided with an elongated outlet parallel to the partition in the diffluent deck, another diffluent deck below the confluent deck with its partition arranged at right angles to the discharge opening in the confluent deck above, a confluent deck located below the last named diffluent deck of similar construction to the second deck and arranged with its outlet parallel to the outlet in the plane of the partition of the diffluent deck next above.

FRANK EDWARD LICHTENTHAELER.
